UNITED STATES PATENT OFFICE.

JEROME F. RYKOSKEY, OF BENWOOD, WEST VIRGINIA.

REINFORCEMENT FOR SIDE FRAMES OF CAR TRUCKS.

Application filed July 2, 1925. Serial No. 41,083.

This invention relates broadly to side frames for car trucks, and more particularly to a reenforcement for the arch bars of such frames.

5 The primary object of the invention is to provide, in association with a railway truck frame of the so-called "diamond side" type, a simple, effective and readily applicable form of reenforcement for the arch bars of 10 said frame.

A further object is to provide a reenforcing device or structure of the character mentioned which shall function not only to minimize the tendency of the arch bars to 15 break under stresses imposed thereon, but also to so confine and support those portions of the arch bars located at and adjacent to the points at which breakage thereof most frequently occurs that, in the event of 20 breakage at any of said points, displacement of the sundered parts is effectively prevented, thus materially to reduce the liability to accident which is incident to such displacement.

25 A still further object is to provide a device of the character mentioned having therein openings affording opportunity for inspection of those portions of the arch bars most susceptible to fracture in use.

30 With these and other important objects in view, the invention consists in the features of construction, combinations of elements, and arrangement of parts which will herein-after be fully described, reference being had 35 to the accompanying drawings, in which—

Figure 1 is a side elevation of a car truck, illustrating the application of my invention, portions of the truck being shown in dotted lines;

40 Figure 2 is a section on line 2—2, Fig. 1; Figure 3 is an enlarged perspective view of the main brace or support;

45 Figures 4 and 5 are similar views of the outer and inner side, or housing, members for said support;

Figure 6 is a similar view of the tension bar rest; and—

50 Figures 7 and 8 are, respectively, views in side elevation and on a reduced scale of modified forms of housing members or face-plates.

55 Referring to said drawings, 1 indicates the top arch bar, 2 the bottom arch bar and 3 the tie bar of a railway-truck side frame of ordinary diamond-side type.

As a preliminary to describing the inven-

tion in detail, it is here explained that the arch bars 1 and 2 constitute, in effect, the principal members of a bridge structure whereby is supported between the usual 60 journal boxes 5, the bolster 6 and the superposed load, and that said bars in performing their intended function, are necessarily at all times subjected to shocks and carrying strains which are more or less severe according to the weight of the load supported thereby, the conditions of operation and handling of the cars embodying them, and the conditions of the trackway and roadbed over which said cars travel. These strains 70 result in frequent fracture and breakage of said bars, which most frequently occur at or adjacent to the angles or curves *a* and *b* formed between the horizontal and inclined portions of said bars 1 and 2, which angles 75 or curves are closely adjacent to the bolster columns of the usual railway truck.

Interposed between the arch bars 1 and 2 in closely seated relation to the parts usually occupied by the two bolster columns, is 80 an upright post-like supporting member 7 provided in the form of a heavy casting. Said member 7 has head and base portions 7^a and 7^b at its opposite ends made of sufficiently greater thickness in the direction 85 of the lengths of the arch bars that they will rest upon said bars throughout the extent of the curves *a* and *b* of the latter, said portions having their outer surfaces correspondingly curved to seat conformably upon 90 said bars. Said support 7 is rigidly secured in place by means of a rod or bolt 8 directed vertically through the arch bars 1 and 2 and through a hole 9 provided for said bolt in said support. The lower end or 95 base portion of the support 7 is bifurcated, as shown at 10, to permit inspection through the bifurcation of the upper surface of the bottom arch bar 2, as for detection of fractures.

100 Housing members or face plates 11 and 12 are mounted on the outer and inner sides or faces of the support 7, the same being designed as supports for resisting flexure of the arch bars in outward, or curve-straightening, directions. Securing said face plates 11 and 12 in place are bolts 13 and 14, of which the former is directed through holes 15, 16 and 17 provided therefor in the inner plate 12, the support 7 and the outer plate 11, respectively, and the bolt 14 is directed through other holes 18, 19 and 20 provided

- in said members. The plates 11 and 12 have upper end flanges 11^a and 12^a, respectively, which seat in overlying relation to the adjacent edge portions of the top face 6 of the top arch bar, and have lower end flanges 11^b and 12^b, respectively, which closely underlie the bottom arch bar 2 at the curve *b* of the latter, being introduced between said arch bar and the tie bar 3.
- 10 Said face plates 11 and 12 have formed on their outer faces adjacent to the lower rear edges thereof angularly disposed lugs 21 and 22, respectively, through which attachment to lugs on the spring plank 23 is effected, as by means of small bolts 24.

The inner face plate 12 has an integral angularly disposed bracket 25 formed thereon, and carried by this bracket are lugs 26 adapted for having mounted thereon 20 brake-beam hangers (not shown).

Provided in the face plate 11 adjacent to its upper and lower ends are oblong openings 27 and 28 designed to permit inspection of the outer edge portions of the arch bars 25 1 and 2, respectively, at and adjacent to the curves *a* and *b*.

The inner edge of the outer plate 11 is preferably provided with a shallow recess 29 affording clearance for the bolster 6 and 30 terminating at its lower end in an upwardly facing shoulder 30 located at a suitable elevation, said shoulder being adapted to serve as a rest for said bolster in case the supporting springs 31 for the latter should become 35 displaced.

I prefer to employ in association with the reinforcing structure hereinbefore described a rest for the outer end of the bottom arch bar, or tension bar 2, having substantially 40 the form shown in Figs. 1 and 6, which consists of a flat horizontal bar portion 32 and a brace portion 33, the former being adapted to be interposed between the top of the journal box 5 and the overlying horizontal end 45 portion of said bar 2. The brace portion 33, which is shaped to conformably fit over the edge of the journal box and to seat against the adjacent side of the latter, has its upper surface shaped to closely underlie the bar 2 50 at and adjacent to the curve or bend formed in the bar between the outer end portion and the inclined portion of the latter, as shown in Fig. 1. Obviously, said angular rest constitutes a supporting brace for the bar 2 at and 55 adjacent to the outermost bend of the latter.

The modified form of housing shown in Fig. 7 consists of a single casting or forging which embodies two face plates 11' connected at their lower ends by a horizontal member 34 formed integral therewith, said face plates being designed for mounting at opposite sides of the position occupied by the bolster.

The modified form of face plate shown in 60 Fig. 8 illustrates a face plate made in two

sections 11'' which are relatively adjustable to vary the length thereof to suit frames in which the distances between the arch bars 1 and 2 vary from the usual standard.

What is claimed is—

1. The combination with the top arch bar and bottom arch bar of a truck side frame of diamond type, of a supporting member interposed vertically between said bars, the upper and lower ends of said member resting 70 against the under and top sides, respectively, of said bars, and face plates mounted against the inner and outer faces of said member and having flanges engaged with said bars in opposing relation to the ends of 75 said member.

2. The combination with the top arch bar and bottom arch bar of a truck side frame of diamond type, of a supporting member interposed vertically between said bars, the upper and lower ends of said member resting 80 against the under and top sides, respectively, of said bars, and face plates mounted against the inner and outer faces of said member and having flanges engaged with 85 said bars in opposing relation to the ends of said member, the outer of said plates being provided with inspection openings.

3. The combination with the top arch bar and bottom arch bar of a truck side frame 90 of diamond type, of a supporting member interposed vertically between said bars, the upper and lower ends of said member resting against the under and top sides, respectively, of said bars at and adjacent to the inner 95 angles formed in the latter, and face plates mounted against the inner and outer faces of said member and having flanges seated upon 100 said bars in opposing relation to the ends of said member.

4. The combination with the top arch bar and bottom arch bar of a truck side frame of diamond type, of a supporting member interposed vertically between said bars, the upper and lower ends of said member resting 110 against the under and top sides, respectively, of said bars at and adjacent to the inner angles formed in the latter, and face plates mounted against the inner and outer faces of said member and having flanges seated 115 upon said bars in opposing relation to the ends of said member, the outer of said plates having therein openings permitting inspection of the thereby-enclosed angular portions of said bars.

5. The combination with the top arch bar and bottom arch bar of a truck side frame of diamond type, of a supporting member interposed vertically between said bars, the upper and lower ends of said member resting 120 against the under and top sides, respectively, of said bars at and adjacent to the inner angles formed in the latter, and face plates mounted against the inner and outer faces of said member and having flanges seated upon 125

130

said bars in opposing relation to the ends of said member, said supporting member having its lower end bifurcated.

6. The combination with a diamond frame truck having a top arch bar, a bottom arch bar, and a tie bar, of a post-like member interposed between said bars at the bends of the latter, and face plates attached to the outer and inner faces of said member, said plates having end flanges seating upon said bars in opposing relation to the ends of said member.

7. The combination with a diamond frame truck having a top arch bar, a bottom arch bar, and a tie bar, of a post-like member interposed between said bars at the bends of the latter, said member having a bifurcated lower end, and face plates mounted on the opposite sides of said member, said plates having their ends extending past said bars and carrying portions in seated relation to the bars at the sides opposite said member.

8. The combination with a diamond frame truck having a top arch bar, a bottom arch bar, and a tie bar, of a post-like member interposed between said bars at the bends of the latter, and face plates attached to the outer and inner faces of said member, said plates having end flanges seating upon said

bars in opposing relation to the ends of said member, the lower of said flanges being interposed between the bottom arch bar and said tie bar.

9. The combination with a diamond frame truck having a top arch bar, a bottom arch bar, and a tie bar, of a post-like member interposed between said bars at the bends of the latter, said member having a bifurcated lower end, and face plates mounted on the opposite sides of said member, said plates having their ends extending past said bars and carrying portions in seated relation to the bars at the sides opposite said member, the outer of said bars having inspection openings therein exposing the bars at their said bends.

10. Means for reinforcing the arch bars of diamond frame trucks, comprising, in combination with the top arch bar and the bottom arch bar, a post-like member interposed between said bars at the bends of the latter, and side plates carried by said member having their ends in seated relation to said bars opposite the points of seating engagement of said member with said bars. 55

In testimony whereof, I affix my signature.

JEROME F. RYKOSKEY.
